UNITED STATES PATENT OFFICE.

LOUIS J. R. HOLST, OF NEW YORK, N. Y., ASSIGNOR, BY MESNE ASSIGNMENTS, TO
LITHOTEX CORPORATION, OF NEW YORK, N. Y., A CORPORATION OF NEW YORK.

MEANS FOR COMPUTING CIRCUMFERENCES OR FRACTIONS THEREOF.

1,148,588.

Specification of Letters Patent.

Patented Aug. 3, 1915.

Application filed June 10, 1910. Serial No. 566,254.

To all whom it may concern:

Be it known that I, LOUIS J. R. HOLST, a citizen of the United States, residing in the borough of Brooklyn, city of New York, 5 county of Kings, and State of New York, have invented certain new and useful Improvements in Means for Computing Circumferences or Fractions Thereof, of which the following is a specification.

10 This invention relates to devices for computing circumferences or fractions thereof, and the present embodiment of the invention has been found especially useful for determining the proper height of a design to be reproduced a number of times on a printing surface from which the reproductions are transferred to a metal roller for printing purposes.

Inasmuch as the present embodiment of 20 the invention was particularly gotten up for this use, I will describe its construction and operation as actually used in determining the desired height of designs to be transferred to such rollers. These rollers are 25 used for printing continuous or disconnected designs on textile fabric, wall paper, etc., for which purpose it is necessary that the design as a whole which is to be formed on the metal roller, must completely cover 30 the surface of the roller with the ends of the design exactly meeting and registering, so that the design will appear continuous when printed from the roller. One method now known of producing designs on such a 35 roller, is to take a unit of the selected design and reproduce it photographically a number of times on adjacent portions of a sensitized surface so as to form, when the plate is developed, a complete design of a 40 number of reproductions of such unit.

From this plate a zinc plate may be made up and properly etched, either of the same size as the developed photographic plate, or of a different size, the zinc plate being of a 45 length equal to the circumference of the roller on which the design is to be transferred. The design is then transferred from the zinc plate by inking the plate and rolling the roller upon the same. Inasmuch as 50 it is necessary for the ends of the design to meet and register within one or two thousandths of an inch, it is important that the size of the stepped-up unit design should be accurately determined, and this device is

useful in computing the size of such 55 stepped-up designs.

In practice, it is desirable, for purposes of economy, to step up the design in a size smaller than the size of the design as transferred upon the roller, and to subsequently 60 enlarge the design to the size which it is desired to produce it in. One known practice is to step up the designs in two-thirds of their size as subsequently transferred to the roller; and the present embodiment of 65 my invention is one in which the designs may be computed in this size.

The invention will be more readily understood from the following description taken in connection with the accompanying drawings, in which—

Figure 1 represents a front view of the device; Fig. 2 a vertical sectional view; Fig. 3 a horizontal sectional view through the lower end of the device; Fig. 4 is an enlarged view of the vernier; and Fig. 5 is a detail end view of the base.

The device consists of a pair of compass legs 10 and 11, the lower end of the latter being pivoted on a stud 12 projecting from 80 the lower end of the frame 13 while its upper end is pivoted by means of the pin 14 to the co-operating leg 10.

The lower end of the leg 10 is pivoted to a block 15 by means of a pin 16, and this 85 block slides in guideways 17 at each side of a slot 18 in the lower end of the frame 13.

The block 15 is regulated in its movements by a screw 19 having the thumb wheel 20 at its outer end. The inner end of the 90 pivot 14 is provided with a convex head 22 which bears against the upper end of the frame and partly relieves the lower pivots from unnecessary strain.

Located above the block 15 is a scale 23 95 divided into 80 even divisions while the block itself carries a scale 24, divided into 25 parts and constitutes in conjunction with the scale 23 a vernier reading to 1/1000.

The diameters of the rollers used in the 100 above referred to process are measured and indicated by means of the ordinary standard sliding micrometer calipers; but so far as my present invention is concerned in its broad aspect, these diameters may be measured and indicated by any suitable means and scales. In the present form of my invention, the scale 23 is graduated to read in 105

fractions of circumferences the diameters of which correspond to the divisions of the regular standard micrometer scales used in measuring the diameters of the rollers; that is, the divisions on this scale 23, while corresponding numerically to those of the micrometer scale, are a fraction of π times the divisions on the micrometer scale used in measuring the diameters of the rollers, 10 so that when the diameter of the roller is measured with a sliding micrometer and its reading, which we will say is three and a half, is reproduced upon the scale 23, the scale 23 will indicate on this instrument a 15 fraction of the circumference corresponding to the diameter three and a half, as indicated on the regular sliding micrometer. For instance, if, as in the present form of my invention, the scale 23 is graduated in 20 divisions of one-third of π times the divisions of the diameter-measuring scale, if the diameter-measuring scale indicates a 3 1/2 inch diameter and the scale of my device is set at the 3 1/2 mark, the distance 25 between the points 12 and 16 will be equal to one-third of the circumference of a roller the diameter of which is 3 1/2 inches.

The feature of making the scale to read in fractions of the circumference of the 30 roller is useful in computing the height of designs for the purpose of stepping them up in a reduced size, as will hereinafter appear, but it does not alter the principle of operation of the device to have the scale 23 35 graduated in units of πD instead of in units of a fraction of πD , since the reduction may be obtained by properly numbering the scales along the legs 10 and 11 from which the height of designs is computed, as will 40 now be described.

The center lines of both legs 10 and 11 are provided with scales 25 which are graduated and numbered from 3 to 20, the graduation being in fractions of the length of 45 the legs, each graduation being placed at a point representing a definite fraction of the distance along the legs between the point 14 and the points 12 and 16 at the free extremities of the legs. In the present embodiment of the invention, which is to be used in determining the height of designs two-thirds of their final size as transferred to the roller, each graduation is numbered 50 double the fraction of the distance that it actually represents along the legs, so as to give the proper computation in connection 55 with the one-third size scale 23 for a two-third size image desired. For instance, if the divisions of scale 23 had been in π times 60 the divisions of the micrometer scale for measuring diameters instead of a constant times π times these divisions and it were desired to compute the actual height of an image four of which were to exactly meet 65 around the roller, after setting the scale 23

corresponding to the diameter of the roller, the height of the image would be computed by measuring the distance between two points each one-fourth of the way down the legs 10 and 11 from their hinged point; 70 but since the divisions of the scale 23 are in one-third of π times the scale of the diameter-measuring instrument, and since it is desired to compute the height of the 75 unit designs in two-thirds the size in which they are to be transferred, it is necessary to double the numbers along the scales of the legs to increase the otherwise one-third size to two-thirds. For example, the points 4 on the scales of legs 10 and 11 are exactly 80 mid-way between point 14 and points 16 and 12, thereby dividing the scale into two equal parts, and the distance between points 4 and 4 is one-half the distance between the points 12 and 16; so that if the scale 23 had been graduated in units of π times the diameter of the roller instead of one-third π times the diameter, the points 4 would have been indicated as points 2, indicating the 85 height of the design two of which would completely encircle the roller; but since the size in which the design is to be stepped and repeated is to be two-thirds of the size in which it is to be applied to the roller, it is found more convenient to make the computation by making the divisions of scale 23 one-third π times the divisions of the diameter-measuring scale, and then doubling the value of the indicating numerals 90 along the scales of the legs so as to correctly indicate the desired height of the image which would otherwise be on a one-third scale instead of a two-thirds scale.

In practice, rollers vary from 3-1/2" to 5-1/2" in diameter. When therefore, the 105 zero of the vernier is set to the 3-1/2 mark on the scale, it brings the centers 12 and 16 to a distance of 3.665" or a distance equal to 1/3 of the circumference of a 3-1/2" roller. When at the maximum mark on the scale, it brings the centers 12 and 16, 2.094" 110 farther apart, which represents the distance of 1/3 of the circumference of a 5-1/2" roller.

The manner of computing the desired 115 fractions of a circumference with the device herein described, is as follows: If it is desired to place a design upon the roller, which design is to comprise four repetitions of the unit design in vertical alinement or around the circumference of the roller, and if it is desired to step and repeat the design in a 120 size two-thirds of the size in which it is to be transferred to the roller, the height of the design as repeated must be 2/3 of 1/4 of the circumference of the roller, which is equal to 125 1/6 of πD . To obtain this proportion of two-thirds of one-quarter of the circumference, the diameter of the roller is measured by a suitable sliding micrometer caliper the 130 scale of which corresponds to the scale of

this device. A reading of the scale of the micrometer is observed and the scale 23 of this device is set to correspond to the reading on the micrometer caliper, at which setting the distance between the points 16 and 12 will be equal to $1/3$ of π times the diameter of the roller, and the distance between the points 4 on the scales of the leg will be twice one-fourth of this distance, *i. e.*, twice 10 one-fourth of the distance $1/3 \pi D = 1/6 \pi D$, which is the proper height for each of the four images. If it were desired to place six images around the circumference of the roller, the height of each image would be 15 equal to the distance between the points 6—6 on the legs, etc. It will thus be seen that by the proper graduation of the scales 23 and 25, or either of them, the circumference or any desired fraction of a circumference may 20 be readily computed.

Having thus described my invention, what I claim as new and desire to secure by Letters Patent, is:

1. In a circumference computing device, 25 the combination of a support, a pair of legs pivoted together at one of their extremities, means pivotally connecting the other extremity of one of said legs to the support, a screw connected to the other leg to move the 30 same for varying the distance between the legs, means for guiding said leg in its movements to cause a point at the lower extremity of said leg to move in a straight line causing the other leg to swing about its pivot on the 35 support, and a scale operatively related to

the screw-operated leg along the path of movement of said point for determining the setting of the legs, said scale reading in units of circumferences and each leg being provided with a scale graduated in fractions 40 of its length for computing fractions of the distances between the legs as indicated on the first scale.

2. In a circumference computing device, the combination of a support, a pair of legs 45 pivoted together at one of their extremities, means pivotally connecting the other extremity of one of said legs to the support, a straight guideway for guiding the corresponding extremity of the other leg, a block 50 movable on said guideway and pivotally connected with the extremity of said last leg, a screw for moving the block along the guideway, and a scale operatively related to the guided extremity of said leg for determining the setting of the legs, the divisions of the scale being π times or a constant multiplied by π times of the corresponding divisions of a scale for indicating diameters, each leg being provided with a scale graduated in fractions of its length for computing fractions of the distances indicated on the first scale. 55

In witness whereof, I have hereunto set my hand this 4th day of May, 1910.

LOUIS J. R. HOLST.
